UNITED STATES PATENT OFFICE.

SIDNEY GEORGE BROWN, OF NORTH ACTON, ENGLAND.

TELEPHONE RECEIVER.

Application filed May 3, 1923. Serial No. 636,413.

To all whom it may concern:

Be it known that I, SIDNEY GEORGE BROWN, a subject of the King of Great Britain, residing at Victoria Road, Willesden Lane, 5 North Acton, in the county of Middlesex, England, have invented certain new and useful Improvements in or Relating to Telephone Receivers, of which the following is a specification.

10 This invention relates to telephone receivers or head phones and has for its chief object to enable such devices to be made more economically than heretofore, without impairing their efficiency. Head phone receivers as at present made usually comprise an ebonite or other composition cap, which fits against the ear of the listener, which cap is screwed upon the edge of a light aluminium or other metal case carrying the diaphragm and a receiving electromagnet the poles of which approach closely to the inner 20 face of the diaphragm.

In such receivers the pole pieces have hitherto been of iron, the magnet consisting 25 of a stamping or stampings. According to one feature of this invention (which is applicable to various types of telephone receiver) the magnet stamping is stamped out of sheet metal and is itself formed with integral tongues which when bent up constitute the pole pieces, the tongues being so shaped and situated in the stamping as, when bent up, to form adjacent upright pole pieces the combined lengths of which are 30 considerably greater than the distance separating them. For this purpose, in one form of stamping in which the magnet may be of ring or part ring form, the tongues are formed in the stamping so as to extend past 35 or overlap each other and on bending up to form pole pieces which are staggered or side by side. Or the stamping may have tongues at one side which are directed towards each other and can be bent up so as to form pole 40 pieces having their vertical edges adjacent. Or the stamping may be bent up so as to constitute a ring of pole pieces instead of the pair usually supplied, provided with 45 separate coils or a single ring coil common to the group. In any case the poles can be as closely adjacent to each other as is required, while providing for the necessary 50 length of the pole pieces to carry the receiver coils.

55 According to a further feature of this invention the aluminium or other light metal

casing, on which the vulcanite or like cup is screwed, is formed with a series of bosses at its rim, by buckling out or otherwise bossing the thin metal, and the screw thread by 60 which the cap is secured is formed in the bosses. The screw is therefore an interrupted one and the thread is formed in thickened or strengthened parts of the metal so that there is no need to provide a thickened rim for the case, which can therefore be of thin metal throughout.

In order that the said invention may be clearly understood and readily carried into effect, the same will now be described more 70 fully with reference to the accompanying drawings, in which:—

Figure 1 is a side elevation of the receiver with the vulcanite cap removed,

Figure 2 is a face view showing the interior of the receiver,

Figure 3 is a cross section of the complete receiver,

Figures 4 and 5 are, respectively, face and side views of a magnet stamping showing 80 one form of the invention; and

Figures 6 to 9 show modified forms of sheet metal magnet stamping.

A is the receiver casing. B is the vulcanite or other cap perforated in the usual manner 85 and screwed upon the casing A. C is the diaphragm gripped at its edges between the casing and cap. D is the magnet which is stamped from sheet metal with integral pole pieces d which are afterwards bent up on 90 which the receiving coils E are mounted.

In the form of magnet shown in Figures 1, 2 and 3 an approximately semi-circular stamping is employed and the blank is stamped out of sheet metal in the form 95 shown in Figure 4, the integral pole piece tongues d being indicated in dotted lines before turning up to form the pole pieces. It will be seen that these tongues when flat extend past each other so as to lie side by side 100 and therefore when they are turned up at right angles, as indicated in Figure 5, they are spaced sufficiently apart to accommodate the receiver coils E but are separated by a distance which is considerably smaller than 105 their combined lengths and in fact is, as shown, smaller than the length of either pole piece. This length of pole piece is obtained by causing the tongues to extend past or overlap each other so that when bent up 110 they form pole pieces which are staggered and are, therefore, not limited in length by

the distance separating them. It is, of course, obvious that if desired the tongues may be arranged so that the pole pieces are placed side by side, that is, with their edges adjacent and separated by a convenient distance, the spacing of the pole pieces depending upon the shape and disposition of the tongues.

The magnet is secured in the casing by 10 screw studs F passing through the stud holes d^1 in the part of the magnet stamping adjacent to the pole pieces, these studs passing through insulating bushes and form terminals for connecting up the receiving coils 15 E through the tongues f.

To permit of the casing A, usually of aluminum or aluminum alloy, being made as light as possible without unduly reducing its strength at the screw threaded portion, 20 the casing is stamped up near its rim with a number of shallow bosses a, forming slight recesses as seen from the inside and indicated in Figure 3, these bosses being screw threaded so that the thread when cut is entirely external to the main surface of the casing and the casing is thus not weakened as is usually the case by a screw thread cut completely around its circumference and, therefore, effectively thinning the metal at 25 the part receiving the perforated cap B. The screw threaded bosses a preferably lie just within the edge of the casing so that the edge itself is of uninterrupted circular form. The bosses are shallow and are just 30 sufficient to receive the thread. Any convenient number of bosses may be employed, the receiver shown in the drawings having four.

Figure 6 shows a slight modification of the 40 magnet form in which the stamping D¹ forms somewhat more than a semicircle and the tongues or pole pieces d^1 are directed inwardly, parallel to each other so that when bent up they stand side by side with adjacent edges. The space between is made sufficient to accommodate the coils.

In Figure 7 the stamping D² is in the 45 form of a cross and two pairs of pole pieces d^2 , alternately N and S, are made by bending up the tongues which radiate from the centre to form the cross.

In Figures 8 and 9 a stamping D³ is made of star form, with four longer and four shorter radiating tongues d^3 and d^4 which when bent up form an outer and an inner 55 ring of pole pieces of opposite polarities as indicated. This allows a single magnet coil E¹ to be employed between the two pole rings. Obviously the number of pole pieces may be varied according to the size of the 60 magnet.

What I claim and desire to secure by Letters Patent of the United States is:—

1. A magnet for telephone receivers comprising a sheet metal stamping having pole 65 pieces integral therewith and bent up substantially at right angles to the plane of said stamping, as set forth.

2. A magnet for telephone receivers comprising a stamping having integral extension 70 pieces thereon extending past each other which when bent up substantially at right angles to the plane of said stamping form pole pieces, as set forth.

3. In a telephone receiver the combination 75 including a magnet formed from sheet metal stamping, pole pieces integral with said magnet and bent up substantially at right angles to the plane of said magnet, and electrical windings mounted on said pole 80 pieces, as set forth.

4. A magnet for telephone receivers comprising a sheet metal stamping partly circular in outline, two inwardly projecting 85 tongues integral therewith and parallel to one another which form pole pieces when bent up substantially at right angles to the plane of said stamping, as set forth.

5. A telephone receiver including in combination a magnet formed from sheet metal 90 stamping, pole pieces integral with said magnet and bent up substantially at right angles to the plane of said magnet, electrical windings mounted on said pole pieces and a diaphragm adapted to be vibrated by said 95 magnets, as set forth.

6. In a telephone receiver, a screwed outer cap and a case having a number of shallow bosses in its rim, which bosses are screw threaded to receive the said cap.

SIDNEY GEORGE BROWN.
